PILE FABRIC AND METHOD OF MAKING
THE SAME

Frank M. Kaufman, Merion, Pa., assignor to Collins & Aikman Corporation, Philadelphia, Pa., a corporation of Delaware

Application April 12, 1933, Serial No. 665,725

4 Claims. (Cl. 139—398)

My invention is a pile fabric having a ground or back with which pile loops or tufts of unequal length or height are interlaced to form irregular face, and the method of weaving such fabrics. 5 In fabric embodying my invention, the ground or back contains wefts with which pile warps are interlaced so that each pile warp forms alternately long and short pile loops. Preferably the pile warps interlaced in a ground are grouped in pairs 10 and the long loops formed by one of the pile warps of a pair are staggered with relation to the long loops formed by the other pile warp of such pair, and a short pile loop formed by one warp of the pair is adjacent to the long pile loop formed 15 by the other warp of the pair. The pile warps are preferably looped in the form of V's over alternate wefts of the ground, and the long and short loops may be supported by face wefts, which, however, may be removed after weaving. The 20 loops may be left uncut to form a frieze type fabric or may be cut to form cut pile tufts of unequal lengths.

Such fabrics may be woven double, in accordance with my invention, upon a loom having three 25 sets of pile loop gauges, such as wires or cords extending warpwise of the loom; one set of gauges being disposed in a substantially horizontal plane between the other two sets of gauges. The intermediate set of gauges supports and aids in the 30 formation of long loops of both a top fabric and a bottom fabric. The upper set of gauges supports and aids in the formation of short loops for the top fabric, and the lower set of gauges supports and aids in the formation of short loops 35 for the lower fabric. Preferably a double shuttle loom is utilized in weaving the fabrics double and pairs of wefts are laid simultaneously, but a single shuttle loom may be employed.

In weaving my novel fabrics double, there are 40 utilized ground warps for each fabric, pile warps for each fabric and pairs of picks positioned one above the other. The pairs of picks are laid in a cycle in which, it may be considered, one pick of the first pair is interlaced with the ground 45 warps and all the pile warps of the top fabric and the other pick of the first pair is interlaced with the ground warps and all the pile warps of the bottom fabric. One weft of the second pair supports short loops formed by certain pile warps 50 of the bottom fabric and the other weft of the second pair supports long loops formed by other pile warps of the bottom fabric. The respective wefts of the third pair interlace with the ground warps of the top fabric and bottom fabric respectively. One weft of the fourth pair supports 55

long loops formed by certain pile warps of the top fabric and the other weft of the fourth pair supports short loops formed by other pile warps of the top fabric. The cycle is then repeated but with the pile warps which formed long loops in 5 the first sequence forming short loops in the second sequence, and vice versa.

The characteristic features and advantages of my method and the product thereof will further appear from the following description and the 10 accompanying drawing in illustration thereof.

In the drawing, Fig. 1 is a longitudinal sectional view illustrating diagrammatically the arrangement of yarns and gauges in the weaving of double fabric in accordance with my invention 15 and Fig. 2 is a graph illustrating diagrammatically the shedding of warps and top and bottom gauge sets during the picking of the wefts of a complete series.

As illustrated in the drawing, the fabrics are 20 woven in duplicate on a double shuttle loom having a set of upper gauge wires A supported at their left hand end (Fig. 1) by the shedding mechanism of the loom, a set of lower gauge wires B supported at their left hand ends (Fig. 1) by 25 the shedding mechanism of the loom, and a set of stationary gauge wires C disposed in a horizontal plane between sets A and B.

By the utilization of such mechanism and of 30 my improved method, there may be produced a top fabric and a bottom fabric each having a ground and long and short pile loops. Such fabrics separate from one another as they weave down off the gauges A, B and C and towards the right (Fig. 1) and are taken off by the pin rollers 35 of the loom.

The weaving of the top fabric involves the shedding of gauges A, of ground warps A¹ and A², and of pile warps A³ and A⁴. The weaving 40 of the bottom fabric involves the shedding of the gauges B, of ground warps B¹ and B² and of pile warps B³ and B⁴.

At the beginning of the weaving of the fabric fragment shown in Fig. 1, (starting at the right) 45 the shedding mechanism elevates the warps A¹, A³, A⁴, A¹ and gauge B and depresses warps A², B², B³, B⁴ and gauge A so as to permit the simultaneous laying of the pick 5^a in interlacing relation with the ground warps and pile warps of the top fabric and of the pick 5^b in interlacing 50 relation with the ground warps and pile warps of the bottom fabric.

Before the next picking action, the shedding mechanism elevates the warps A², B³, gauge A, 55 depresses the warps B¹, gauge B, moves the warps

B⁴ to intermediate position and leaves the remaining warps as they previously were. When the shuttles lay the picks 6^a and 6^b they are supported respectively on the gauges C and B and support respectively the warps B³ and B⁴ and form respectively long loops c and short loops b on the bottom fabric.

The shedding mechanism then elevates the warp B² and gauge B, depresses the warp A¹ and gauge A moves the warps A³, A⁴ and B³ to intermediate position, leaving the remaining warps as they were on the previous picking motion. The laying of the picks 7^a and 7^b interlaces them respectively with the ground warps A¹ and A² and with the ground warps B¹ and B².

On the next shedding movement, the warps A¹ and gauges A are elevated, the warps B², A³, B⁴, B³ and gauges B are depressed, and the remaining warps are left as they were on the last previous picking motion. The pick or weft 8^a is then laid and is supported against the gauges A and supports the short loops a' formed by the warps A⁴. The companion pick or weft 8^b is laid and supported against the gauges C and supports the long loop c' formed by the warp A³.

The next shedding motion elevates the warps B¹, A⁴, A³ and the gauges B; depresses the warps A² and the gauges A and leaves the remaining warps in their last preceding position. The pick 9^a is then laid and interlaces between the ground warps A¹ and A² and anchors the warps A³ and A⁴ in the ground. Simultaneously or sequentially the pick 9^b is laid and interlaces with the ground warps B¹, B² and anchors the pile warps B³ and B⁴ in the ground of the bottom fabric.

During or after the beat-up of the picks 9^a and 9^b, the shedding motion elevates the warps A², B⁴ and gauges A; depresses the warps B¹ and gauges B; and moves the warps B³ to an intermediate position, the remaining warps being left in their last preceding position. The pick or weft 10^a is then laid and is supported by the gauges C and supports the long loops b' formed by the warps B⁴. Simultaneously or sequentially therewith the pick 10^b is laid, is supported by the gauges B, and supports the loop c' formed by the warps B³. There is thus formed across the fabric a second row of long and short loops on the bottom fabric, the warps which form the small loops of the first row forming the long loops of the second row, and vice versa.

The next shedding motion elevates the warps B² and the gauges B; depresses the warps A¹ and gauges A; moves the warps A³, A⁴ and B⁴ to an intermediate position, and leaves the remaining warps in their last preceding position. The pick 11^a is now laid to form a ground weft between the ground warps A¹ and A² of the top fabric and the pick 11^b is concurrently or sequentially laid to form a weft interlaced with the ground warps B¹ and B² of the bottom fabric.

The next movement of the shedding mechanism elevates the warps A¹ and the gauges A; depresses the warps B², A⁴, B⁴, B³ and gauges B and leaves the remaining warps in their last previous position. The pick 12^a is then laid to form a face weft resting against the gauges A and supporting the short loops a'' formed by the warps

A². The pick 12^b is concurrently or sequentially laid to form a face weft resting against the gauges C and supporting the loops c''' formed by the warps A⁴. There are thus formed across the top fabric a second row of long and short loops, the warps which form the long loops of the first row forming the short loops of the second row, and vice versa.

After the fabrics pass off the free ends of the gauges they separate and the wefts connecting the selvages of the two fabrics may be readily cut and the face wefts pulled if desired.

By my invention I am enabled to produce rapidly and economically fabrics having long and short loops providing a good coverage of the ground with a minimum use of pile yarns, and if desired, the loops may be cut so as to provide pile tufts of different lengths simulating the uneven lengths of the hairs of natural fur.

Having described my invention, I claim—

1. A pile fabric comprising a ground containing ground wefts and pairs of pile warps interlaced therein, each pile warp forming alternately a long loop and a short pile loop and the short loop of one warp of a pair being aligned with a long loop of the other warp of such pair, and the warps of such pair being looped under the same ground wefts.

2. A pile fabric comprising a ground including weft threads, pile warps looped around weft threads aforesaid and forming rows of loops of unequal lengths between said weft threads, a ground weft over which each of said rows is looped and face wefts supporting respectively a row of long loops and a row of short loops.

3. In the weaving of double fabrics, the steps which consist in laying yarn to form a weft in each of a pair of spaced grounds, next laying yarn to form wefts supporting respectively pile loops of different lengths interlaced in one of said grounds only, next laying yarn to form a weft in each of said pair of grounds, and next laying yarn to form wefts supporting respectively pile loops of different lengths interlaced in the other of said grounds only.

4. In the weaving of double fabrics on three sets of pile loop gauges arranged with one set of gauges between the other two sets of gauges, the steps which consist in laying yarns to form a weft above the upper set of gauges and a weft below the lower set of gauges, interlacing with each of said wefts ground warps and pile warps, laying yarns to form a weft between the intermediate set and upper set of said gauges and to form a weft between the intermediate set and the lower set of said gauges, interlacing with said last named wefts pile warps interlaced with one of said first named wefts, laying yarns to form a weft above the upper set of gauges and a weft below the lower set of gauges, interlacing with each of said wefts ground warps, laying yarns to form a weft between the intermediate set and upper set of said gauges and to form a weft between the intermediate set and the lower set of said gauges and interlacing with said last named wefts pile warps interlaced with the other of said first named wefts.

FRANK M. KAUFMAN.
